UNITED STATES PATENT OFFICE.

PHILIP C. DONNER, OF NEW YORK, N. Y.

MACHINE FOR CUTTING FUR.

SPECIFICATION forming part of Letters Patent No. 688,296, dated December 10, 1901.

Application filed July 12, 1901. Serial No. 68,038. (No model.)

To all whom it may concern:

Be it known that I, PHILIP C. DONNER, a subject of the Emperor of Germany, and a resident of the city, county, and State of New York, have invented certain new and useful Improvements in Machines for Cutting Fur, of which the following is a specification.

My invention relates to machines for cutting fur, and has for its object mainly to provide mechanism for effectively and rapidly feeding the material to the knives or cutters and to prevent the clogging of the hopper through which the material passes on its way to the knives.

15 The invention will be fully described hereinafter and the features of novelty pointed out in the appended claims.

Reference is to be had to the accompanying drawings, in which—

20 Figure 1 is a side elevation of a fur-cutting machine with my improvements applied thereto. Fig. 2 is a plan thereof, and Fig. 3 is a sectional elevation of the upper part of the machine on line 3 3 of Fig. 2.

25 A is an elevator or other feeding device which conveys the material to the hopper B. This hopper is disposed at the upper end of the machine, and at the bottom of the hopper are located the knives or the cutting mechanism, which may be of any suitable construction, and, as shown, comprises a rotary knife C on a shaft C', which rotates by means of a belt C² from the pulley D' on the main shaft D. E is the belt for driving the said shaft 30 through the medium of the pulley D².

Within the hopper is arranged to reciprocate vertically, adjacent to one side, a plunger F, preferably formed with a plate F', which flares upward and outward. The plunger F 35 has two rods F², moving in guides G and having at their outer ends downwardly-bent members F³. The lower ends of these members are connected pivotally at H' with links or connecting-rods H, connected at their other ends with bars I. On one side of the machine the pin which connects the rod H and bar I is a crank-pin J on a disk J', mounted on a shaft J². This shaft is rotated by means of gear-wheels J³ K and a belt or cord L. In this 40 manner a reciprocating vertical movement is imparted to the plunger F. Within the hopper is further mounted to reciprocate in a hori-

zontal or, preferably, a slightly-slanting direction a pusher M, having an inclined apron or plate M' extending upwardly therefrom, 55 the said pusher having a stem M², guided in stationary sleeves N. The pusher M is pivotally connected with two links O, which are in turn attached to levers P, fulcrumed at P'. The upper ends of these levers are slotted 60 and receive pins Q', projected from slides Q, which move together with reciprocating rods R, having guided movement in stationary sleeves S and connected at R' with the ends of the bars I. It will be understood that by 65 this arrangement the pusher M and the plunger F will be operated in a certain relation to each other, and the parts should be so arranged that the upward movement of the plunger will coincide with the inward movement of the pusher, so that the following action will take place. The material dropping into the hopper and guided by the flaring plates F' and M', which, as it were, form an auxiliary hopper, passes to the knives and 70 is pushed downward by the plunger F, the pusher M receding from the plunger at that time, so as to allow space for the passage of the material to the knives. When the plunger moves upward, the pusher is projected 75 inward to pack the material into the path of the plunger, and this action being repeated at every stroke the material will be fed uninterruptedly and all danger of clogging the hopper will be avoided.

80 While I have described my invention as applied to fur-cutting machines, it is obvious that the construction described is applicable to other analogous cases where it is desired to feed a material liable to clog the hopper or 85 other passage through which it is supplied.

I claim as my invention—

1. The combination with the feed or hopper having stationary opposing side walls, of a plunger arranged to reciprocate vertically in 90 the hopper, and a pusher arranged to reciprocate in the hopper between the stationary side walls thereof at an angle to the said walls and also at an angle to the path of the plunger.

2. The combination with a hopper or feed, 95 of reciprocating material-feeding devices arranged therein, said devices being provided with diverging upward extensions forming together an auxiliary hopper.

3. The combination of a hopper or feed, of a plunger arranged to reciprocate therein, a pusher arranged to reciprocate at an angle to the plunger in the hopper and upwardly-dि
5 verging extensions secured to the plunger and pusher respectively and forming together an auxiliary hopper.

4. The combination with a hopper or feed, of a plunger held to reciprocate in said hopper, to a pusher arranged to reciprocate in the hop-

per at an angle to the plunger, levers fulcrumed on stationary parts, links connecting said levers with the pusher, reciprocating rods with which said levers are connected, and a crank mechanism connected with said recip- 15
rocating rods and with the pusher.

PHILIP C. DONNER.
